UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

NEWSPAPER-PRINTING MACHINE

Application filed October 28, 1926, Serial No. 144,877. Renewed March 11, 1930.

This invention relates to a complete printing machine adapted especially for use for printing large daily papers such as are produced usually in the cities of the larger size 5 outside of the few largest cities of the country.

The principal objects of the invention are to provide a complete press, driven one unit from another, in alignment, so as to take up 10 comparatively small space laterally and secure exact synchronism in operation of all the parts of the press, namely the different press units and folder; to avoid the transmission of power from one unit to another through 15 gears, belts, or chains; to design the presses and folder so that their frames can be made up of separate parts united and joined to the other units without finishing the adjacent parts and avoiding the production of noise 20 by the vibration of the elements; to provide a construction which can be set flat on the floor and require no pit and thus reduce the cost of installation and avoid the accumulation 25 of oil and metal which adds to the fire risk; to provide a simple mechanism for taking the weight of the web roll and braking it as necessary; to reduce the number of stoppages for roll replenishment and thus reduce 30 the manual labor and speed up the machine; to provide a path for the web from the web roll to the folder located out of the way at the 35 top of the frame and not adding anything to the floor space required; and in general to so combine these several parts that a machine is secured which will run with few stoppages, 40 comparatively little oversight and produce a completed product in a uniform manner and at the same time will take up a comparatively small amount of floor space. This invention 45 also includes a practical efficient and economical way of combining the subject matter of my prior applications for patent Serial No. 89,070, filed February 18, 1926, No. 655,777, filed August 4, 1922, No. 752,642, filed November 28, 1924, No. 81,761, filed January 16, 1926.

Other objects and advantages of the invention will appear hereinafter.

Reference is to be had to the accompanying 50 drawings in which

Fig. 1 is a front view of a press constructed in accordance with this invention, showing two press units and a folder unit arranged in alignment and driven right through by shafting in a single line;

55

Fig. 2 is an enlarged view showing the connecting parts between the folder and the nearest press unit and also the path of the web from one to the other;

60

Fig. 3 is a view of the right hand side of one of the press units;

Fig. 4 is an end view on enlarged scale of one inking mechanism shown partly in section and including the printing couple;

view, partly in elevation, through the centers of the folding and cutting cylinders;

Fig. 20 is an end view of the same;

Fig. 21 is an end view of the web roll supporting and brake mechanism; and

Fig. 22 is an end elevation of one end thereof.

I have illustrated two press units A and B, placed end to end, that is, with corresponding shafts in alignment. These are also shown as provided with a folder C located at the end of one of the printing units. In this case, the drive is from a motor 10, on the top of a frame through a belt 11 and pulleys to the impression cylinder shaft 12 on one of these units. The machine can be driven by the smaller motor 10^a for threading in and the like. The shaft 12, by gears in the usual way, drives the plate cylinders shaft 13 in the same unit, that is, the unit B and also the other printing couple. The other shaft 12, I call the driving shaft and it is provided with extensions rigidly mounted on each end, coupled directly by couplings 14 and 15 to two other driving shafts. One of these shafts 17 drives another printing unit A and the other shaft 18 drives the folder C. Both the shafts 17 and 18 are driving shafts. The shaft 17 is an impression cylinder shaft. It will be obvious that in addition to the units A and B I can connect these up with other units as desired. Thus this system can be extended as far as practical considerations will allow.

All the press units and folders are driven from a single main shaft 12 on one of them, through an unbroken line of driving shafts arranged end to end and in alignment and without any gears of any sort, or other relatively movable parts, for transmitting the power from one to another. These driving shafts, as well as the main shaft, are all located at the same level, namely the level of all the impression cylinders, so vertical shafts are eliminated with their gears.

This machine is set up throughout in accordance with the process set forth in my Patent No. 1,498,769, granted June 24, 1924. For example it will be seen in Fig. 3 that there are a number of seats on the drawings marked 7. In each of these places the parts of the frame are connected together by the casting of the seats 7 on the two connected parts, or shafts or rods are mounted by the casting of bearings 8 in accordance with said patent. In this way the parts of the machine are assembled without finishing and thus at a material saving in cost. Noise of vibration is also reduced as it is transmitted from one part to another. I have used the numerals 7 and 8 to designate these forms of connection throughout the several sheets of drawings and without reference to the shape and special construction of the various seats and bearings to which it is applied. The ma-

chine can be assembled in the old way, however.

Each printing unit is mounted on a solid base 1. Each frame comprises a part 2 located above the base and supported thereon by four or more soft metal seats 7. These parts 2 of the printing unit frames carry the printing couples and inking mechanism. Above these frames 2 are frames 3 supported by soft metal seats 7 and carrying means for conducting the web away from the printing couples and slitting it.

The folding machine frame 9 and the several press unit frames are connected together by bases 4 at the bottom and by frames 5 and 6 at the top. These several frames are united with the bases 1 or the frames 3 by soft metal seats 7 at their ends. Take for instance the frame 6. It is shorter than the distance between the frame 3 of the printing unit and the frame 9 of the folding unit. The surfaces that are closely adjacent to each other in the assembled structure are cast with depressions to be filled, instead of projections to be finished. These dovetailed depressions are used in the condition in which they are cast. The spaces between are filled with soft metal in the form of seats 7 such as have been described above. The other frames 4 and 5 are connected in the same way. These frames 9 are some of them utilized for other purposes as will appear, but they serve as braces and ties to connect the frames together rigidly at top and bottom. The soft metal seats transmit the vibrations practically without noise and in fact diminish the amplitude of vibration. Bolts are introduced through them, or other fastening devices as may be desired, but are not described herein in detail as they are shown in my prior applications and patent above mentioned.

For supporting the two printing couples I provide a series of studs 21 on each of which is pivotally supported a bearing plate 22 and extending upwardly from the studs. Each of these bearing plates carries a bearing for one of the cylinders so that these cylinders are supported thereby. On the frame 2 there are projections 23 through which extends a screw rod 24, one of course being located at each side of the machine. Each screw rod passes through perforations in the bearing plates 22, the perforations being located in the projections extending up from the bearing plates. The perforations in the bearing plates for the impression cylinders 19 and the perforations in the bearing plates for the plate cylinders 20 are smooth. By means of nuts 25 the impression cylinder bearings are forced up against the projections 23 firmly. By means of adjusting collars 26 the position of each plate cylinder is adjusted along the rod 24 in a most convenient and simple way. In this way all four of the cylinders are accurately located.

and solidly fixed with respect to the frame and the pressure between the cylinders of each couple is regulated. Also the drive is through a stationary, non-adjustable, impression cylinder shaft.

Inking mechanism

A pair of form rolls 28 bear upon the plate cylinder and the ink drum 29 and are driven therefrom. This ink drum is surrounded by the usual distributing rollers 30.

On the driving shaft 13 is a gear meshing with a gear 32 which is carried by a shaft or stud and drives a gear on the shaft 33 on which the ink drum 29 is mounted. This shaft is also provided with a bevel gear 34 driving another bevel gear on an inclined shaft 35 which, by spiral gears 36, drives the ink fountain roll 37. This is located in the ink fountain 38 mounted on projections 39.

The ink fountain is shown as provided with a regulating blade 39^a made up of a plurality of sections, each adjusted independently by a screw 40. These blades are readily adjustable and accessible from the outside of the machine. The adjustment screws 40, which preferably are located one to each column, are supported on a carrier 41 which is fixed on the ink fountain 38.

30 The form roll is adjusted substantially radially with respect to the ink drum by adjusting screws 43 carried in threaded sockets 44 carried by the frame and adjusted by means of spanners applied to nuts 45 on these screws, which engage bearing members 46 on the shafts of the form rolls. In this way the form rolls are moved toward and from the ink drum and adjusted to have the proper pressure thereon.

40 Also mounted on the frame 2 at opposite ends are a pair of projections 48 abutting vertical screws 49 for adjusting a supporting frame 50 at each end. This adjustment moves the form roll substantially to and from the plate cylinder. The bearing member 46 carries a hinged cap to facilitate the removal of the form roll; this cap is held securely in the locked-up position by a clamping screw 51.

50 The distributing rollers are vibrated longitudinally by spiral gears 53 connecting the shaft of the ink drum with a transverse shaft 54 on which is an eccentric pin 55 operating a bell crank 56 pivoted on the frame. This bell crank enters a collar 57 on the shaft of the distributing roll. Preferably each alternate distributing roll is operated in this way.

The ink is supplied from the fountain roll 37 to the ink drum 29 by a ductor roll 60. This ductor roll is mounted on a frame made up of arms 59 extending radially from a shaft 61 and adjustable circumferentially by adjusting screws 58. The arms 59 have open sided bearings for the ends of the ductor roll 60. The shaft 61 is mounted on the frame

and extends to the outside of the frame where it is provided with an arm 62 and an arm 63. This arm 62 is provided with opposite semi-cylindrical recesses for the shaft 61 to which it is secured by bolts 64 on the arm 63, which is free to oscillate on the shaft 61 and adjustably secured to the arm 62 by adjusting screws 65. The arm 63 is provided with a frame 66 which carries an adjusting screw 67. On this screw is a handle 68 which can be swung around to turn the screw and move along it a yoke 69 carrying a cam roll 70.

70 Fixed on the shaft of the fountain roll 37 is a ductor roll cam 71. It is provided with a series of cam surfaces which are wider at one end than at the other. Three sets of these surfaces are shown and they co-operate with the roll 70. When the roll 70 is at the outer end of its travel it will contact with the small end of the raised portions of the cam 71. This part of the cam is of such a nature as to allow this roll to be carried to its extreme position away from the shaft of the fountain roll 37 only a very short period of time, three times per revolution. This means that the ductor roll 60 will engage the ink drum a minimum length of time during each revolution but it will engage it just as many times as if it were adjusted to the other end of the screw 67. In that case the ductor roll 60 will engage the ink drum throughout almost all of the revolution, being dropped from that position briefly three times per revolution. Thus by this variation of the interval or cycle, during which the ductor is in contact with the fountain roll, the amount of ink supply to the distribution system can be varied. Springs 72 tend constantly to pull the ductor roll toward the ink fountain roll and the roll 70 toward the cam 71. Adjusting screws 65 are adjusted to regulate the location of the arm 63 on the shaft 61. They provide a positive connection of that arm with the shaft although it is loosely mounted thereon at the hub. On the shaft of the fountain roll 37 is a ratchet 75 engaged by a spring pressed pawl 76 carried by the ink fountain. The purpose of driving the fountain roll through a ratchet connection rather than a solidly geared connection is to permit the manual rotation of the fountain roll forwardly before the power is supplied to the press so that the ink can be brought up through the distribution system with a minimum loss of unprinted sheets.

Operation of inking mechanism

125 The parts of the inking mechanism are driven in substantially the usual way and they operate as follows: The ink is regulated on the surface of the ink fountain roll 37 by the blades 39 each one being adjusted individually and each accessible from the outside of the press, these fountain rolls and 130

their fountains being located on the outer sides of the two inking mechanisms for each unit. The ink is delivered from the ink fountain roll intermittently to the ductor roll controlled by the adjusting roll 70 and cam 71 so that the ductor roll is in contact with the fountain roll 37 throughout part of its rotation but out of contact with it three times, in the form shown, during each revolution. The ductor roll 60 is brought into contact with the fountain roll whenever it is free to move to that position by the springs 72 which are adjustable as to their pulling power. The distributor rolls, or part of them, are vibrated longitudinally, as has been explained, to more thoroughly distribute the ink on the surface of the ink drum. This drum as usual delivers a film of the desired thickness to the two form rolls 28 which are adjusted in proper relationship to the ink drum and the plate cylinder 20 in the convenient manner explained.

The web supply

Having described the inking mechanism in full, I will now describe the supply of the web to the printing couples in the course of the web through the printing part of the machine in each unit. Each printing frame is provided with a part which supports the web roll R. This support comprises bearings 80 open at the rear and side for receiving the spindle 81 of the web roll. This spindle is first located in a pair of notches 82 in a pair of roll lifting levers 83 which are pivoted on the frame. These levers are lifted to bring the roll up to a position where it will roll down on a pair of flat surfaces 84 and into the bearings 80. The spindle 81 is provided at one end with a brake device comprising a pair of cones 85 and sector shaped concave brakes 86. These brakes are mounted on arms 87 which are pivoted on studs 88 and are connected by a cross piece 89 through which passes a screw 90 operated by a hand wheel 91. By this means the brakes are brought to central position and during running regulate side register. The two pivoted arms 87 are located on opposite sides of the spindle so the brakes are also located on opposite sides. One of these arms is provided with a screw 92 which passes through a poppet 93 in the other and is operated by a hand wheel 94. By turning the hand wheel 94 the brakes can be applied with any desired degree of pressure.

The web W passes from the roll R over a tension roll 95 which is held in a pair of brackets 96 on the frame and pressed into a U-shaped portion of the web to tighten it by springs 97. The tension of the springs is adjustable by hand nuts 98. These parts are shown in Figs. 21 to 22.

The web W passes over idler rolls 99 and

through the printing couple as usual as shown in Fig. 3 receives impressions on both sides. Then it passes up to a slitter roll 100 which is driven from a sprocket wheel 101 on the shaft 12 of one impression cylinder. Above this cylinder roll on the frame 3 are brackets carrying a shaft 102. On this shaft are fixed arms 103 which carry a lever 104. On this lever is a fork having a shaft across it and carrying a rotary slitter 105. In fixed position on the shaft 102 is an arm 107. This arm, by a spring pressed pin 108 and poppet, engages the end of the lever 104 and normally forces the slitter into contact with the slitter roll 100 which is mounted in fixed bearings on the frame 3. The web W comes up over the slitter roll and, in the position illustrated, is slit into two equal parts by the slitter as it passes over.

Fixed on the shaft 102 is an operating handle 109 to which is pivoted a spring-pressed hand latch 110 which is provided with a locking bolt 111 guided in a lug 112 on the handle 109. This locking bolt is adapted to engage in either one of a pair of notches 113 on a projecting arm 114 fixed to the bracket 106. In the position shown in Fig. 16 the bolt engages one of these notches to hold the slitter against the slitting roll positively.

In order to remove the slitter the operator grasps the end of the handle 109 and the latch 110 and pulls the latter toward the handle. This releases the bolt 111. The operator then swings the handle back to a position where the bolt can enter the other notch 113 and hold the slitter away from the slitter roll. But at all times the spring on the pin 108 is ready to force the slitter back to operative position. It will be noted that the bracket 106 is fixed on the frame 3 by a soft metal seat 7.

Both of the printing press units A and B are provided with the same mechanism and the elements or frames 5 and 6 are provided with rolls 115 for guiding the two halves of the web W¹ over toward the folder C. Some of these rolls for guiding the web from the unit A are located on the top of the frame 3 on the unit B.

By reference to Fig. 2 it will be seen that the webs W and W¹ are divided in two and I call the extra webs W² and W³. They are brought along up to the drag roll 116 in substantially the same relationship as that in which they left the slitter 100, being carried over turning bars. They are separated at some point in their travel and are guided over four separate compensator rollers 117. These compensator rollers in each case are mounted on levers 117^a, one end of each of which is provided with a poppet and screw thread for receiving an adjusting screw 118 which is operated by a hand wheel 119 fixed thereon. Four of these are indicated in Fig. 2

for the separate adjustment of the four webs into which the two webs have been slit in the manner described. These parts are mounted on the frame 6.

5 *The folder*

The folding machine which is mounted on the frame 9 has the shaft 18 previously referred to as its main shaft. This is driven from the shaft 12 of the nearest printing unit through a coupling 15 and it carries the folding cylinder. On this shaft 18 is a sprocket wheel 120 which, by a chain 121 drives a shaft 116^a. The chain passes over idler sprockets 122, both mounted on a frame 123 pivoted for adjustment.

10 The shaft 124 is carried by brackets 125 fixed to the frame by seats 7 and carries a bevel gear 126 which is driven by a bevel gear 127 on the shaft 116^a. Carried by the brackets 125 at the two ends of the folding machine is a shaft 128 extending across on which are fixed an arm 129, an arm 130 and an operating lever 131. This operating lever has an 15 arcuate slot 132 into which extends a screw 133 having a projection at the end by which it is screwed up to hold up the lever 131 in any position in which it is placed. The arm 130 has a hole through it for the pin 134 which is pressed by a spring against a shaft 135^a through which the pin passes. One end of the lever 135 is bifurcated and provided with holes for carrying the shaft 135^a. This 20 shaft is free to rotate and is adapted to receive the threaded end of the pin 134. This pin has a head 136 which can be pulled down to take the pressure of a spring 137. Normally the spring forces the lever upwardly at that end and forces a propeller roll 138 25 down on the surface of the drag roll 116. It will be seen that three of these propellers 138 are shown across the machine (see Fig. 13) and they can be all operated simultaneously by the operating lever 131 and each one of 30 them can be released by its nut or head 136 independently of the others.

35 This drag roll is located in position to receive half the width of web from the presses and as each web is slit in two parts it carries four webs. It delivers the slit webs to the former 139 and through forming rolls 140 and nipping rolls 142. One of the latter is yieldingly pressed against the other by a spring pressed pin 143. The web goes down through these between the folding cylinder 145 and the cutting and collecting cylinder 146 which constitutes a part of the couple.

40 It will be remembered that the folding cylinder shaft 18 is coupled by the coupling 15 directly to the impression cylinder shaft of the adjacent printing unit. Also the sprocket wheel 120 on the shaft 18 drives the drag roll. The shaft 18 is mounted on the frame 9 by soft metal bearings 8 at both ends and 45 also the cutting and collecting cylinder 146

has its shaft mounted on the frame by similar bearings so that there need be no finishing of the frame in order to set these shafts and cylinders in proper position thereon.

50 The shaft 18 is provided with a gear 141 which drives a gear 144 on the shaft of the cutting cylinder 146 to drive the same. A gear 147 fixed on the shaft 18 drives a gear 148 loose on the shaft of the cutting cylinder 146. The gear 148 is provided with a cam groove 150 which operates a roll 151 on an arm 152 carried by the pin shaft 153. This shaft also has arms 154 which, in accordance with the action of the cam, drives the pin rods 155. The pins operate in substantially the usual way in the usual guides. The cutting cylinder is provided with a knife 156 and cheek-block 157 which are located and operated as described in my applications above identified. The folding and nipping rolls are driven by a sprocket chain 158 from a sprocket wheel 159 on the shaft of the cutting cylinder.

55 Mounted about the shaft of the folding cylinder is a cam 160 fixed on the frame and having an internal cam surface for operating two rollers 161. These rollers are on an arm 162 carried by opposite longitudinal shafts 163 on the folding cylinder. Arms 164 extend outwardly on the opposite sides of these shafts and in opposite directions. They are connected together by a spring 165 across the end of the cylinder to normally hold these rollers 161 outwardly in contact with the internal cam 160. These shafts 163 also have arms 166 for operating the pin rods 167 mounted in guides 168, for performing the usual function of the pins on the folding cylinder.

60 Also mounted on one of the soft metal bearings 8 and fixed to the frame 9 by a screw 170 is a stationary gear 171 which, as the folding cylinder rotates, operates, through a single intermediate, two gears 172 carried by the cylinder on shafts 173. These shafts are mounted on a part of the cylinder by soft metal bearings 8 constructed like the other bearings of this kind. The shafts 173 carry the usual folding blades 174 and operate them to bring them into the proper position for folding at the bottom of the folding cylinder as is well understood in this art.

65 The folded product passes between a pair of folding rolls 175 centered below the folding cylinder and mounted above on two cross rods 176 by means of depending frames 177. One of these frames is fixed and the other is pressed upon by a pair of springs 178 on guide rods 179 which keep the rolls in close contact. The stationary folding roll is driven by the chain 158. The adjustable folding roll is driven from the stationary one by a pair of gears on the rear ends of the folding roll shafts.

70 Below the folding rolls the folded product

130

of course is delivered to a fan 180. This fan is mounted on a shaft 181 which is driven by a chain 182 from a sprocket wheel 183 on the shaft of the cutting cylinder 146. The fan shaft is mounted in bearings on the frame 9 preferably by means of metal bearings 8 as previously described and its blades are designed as usual for receiving the folded product between them. It is shown in Figs. 14 and 14^a as in position to deliver to the left. It is provided with a guide 186 which directs the product into the fan and stops the rotation of the product when it reaches the lowermost point. The upper end of the guide is fixed to one of two rods 186^a and the bottom on the shaft 191 or 191^a.

I have shown tighteners 187 for the chain 182 and 188 for the chain 189 which drives a sprocket wheel 190 from the fan belt shaft 181. The sprocket wheel 190 is on a shaft 191 on which is the counter disc 192. This counter disc has the usual notch 193 for the counting roll 194. This roll is mounted on an arm pivoted on a shaft 195 and held against the edge of the counter disc 192 by a spring 196. The spring is adjustable by means of a slot 197 in the end for a bolt by which the end is held to a lug 198 on the frame. The shaft 195 supports the guide 185 which extends up between the vanes of the fan for the usual purpose.

The delivery belts 199 are carried by a set of pulleys 200 on the shaft 191 and a set of pulleys 201 carried by a shaft mounted on a pair of brackets 202 constituting a tape delivery frame which is detachable and adapted to be fixed on either side of the main frame 9. These brackets 202 are hung on a shaft 204 and have extended lugs 203 for engaging against the frame of the machine. On this cross shaft also are arms 205 carrying tightener pulleys 206 for the delivery belts 199. It will be seen from Fig. 14^a that these parts are designed to deliver the products at the left in bunches as stated. This counter works in the usual way and the papers come down to the same and are stopped by the guide 186. They are dropped by the fan on the delivery belts 199 and bunched in bunches of 50 or 100, or any other number as may be provided for by the setting of the counter in its construction.

Now referring to Figs. 13 and 13^a it will be seen that the delivery mechanism is reversed but the same elements are employed. In the first place the fan 180 is taken off its shaft and turned around end for end. The drive for the fan is changed so that the driving chain 182, or if desired a different chain 182^a, is driven from a sprocket wheel 181^a on the folding cylinder shaft 18. This obviously reverses the direction of the fan and causes the fan to deliver in the opposite direction. Additional changes are made as follows:

The guides 185 are taken off the shaft 195 and put on the shaft 195^a. The counter and connected parts are taken off the shaft 191, reversed, and put on the shaft 191^a. The roll 194 and its arm on the shaft 195 is placed on the shaft 195^a. It is connected as before with the spring 196 but that spring extends in the opposite direction and instead of being connected with the lug 198 it is connected with the lug 198^a on the same side of the frame. Likewise the tightener 188 which is mounted on the bolt that connects the spring with the lug is placed on the lug 198^a and performs the same function on the belt 189 as before but is on the opposite side. The chain tightener 187 also is used for the same chain 182 but in a different position. The reversal of the fan of course necessitates the reversal of the guides 186. For that purpose they are removed from the shaft 191^a and put on the shaft 191. The papers are stopped going in the opposite direction, but in the same position at the bottom of the fan by the guides 186 located in the new place.

In this way it will be seen that the reversal of the delivery can be brought about in a very simple way by turning the fan end for end and reversing the counter with its parts and the guides, etc. Also the brackets 202 are reversed and put on the other end of the machine. If it is desired to support the longer delivery belts at a point between pulleys 200 and 201, a set of pulleys 207 are used. They are mounted on brackets 208 similar to the brackets 202 pivoted on the same shaft and having lugs 209 at the bottom, performing the same functions as the lugs 203.

It will be seen therefore that the folding machine is driven directly from one of the printing couple shafts of the printing machine without intermediate gearing, that it is all mounted on one frame, and has means for driving the drag roll and carrying the products from the drag roll to the delivery belts on that frame. Also various parts are mounted on this frame by means of seats cast into place to avoid the finishing of the parts of the frame and cooperating elements. The folding and delivery of the products is done by the usual process in machines of this kind, but the reversal of the delivery is an important improvement and there are new details of construction. It will be observed that the parts are so associated as to permit of high speed and economical assembly of the machine. This folder is adapted to be set up with high speed printing press units and to receive the products of a plurality of them and deliver their products in the form of completed newspaper sections at a very high speed all counted automatically.

No claim is made herein to the inking mechanism or folding mechanism by themselves as they constitute the subject matter of divisional applications, Serial No. 405,505, filed

Nov. 7, 1929, and Serial No. 407,963, filed November 18, 1929.

Although I have illustrated and described only a single form of the invention I am aware of the fact that modifications can be made therein by any person skilled in the art without departing from the scope of the invention as expressed in the claims. Therefore, I do not wish to be limited to all the details of construction herein shown and described, but what I do claim is:—

1. In a printing machine, the combination of a plurality of complete printing presses each constituting a printing unit, with means for connecting the impression cylinder shaft in each of said units together end to end in alignment, means for running the several units from these shafts, a pair of plate cylinder shafts beyond the two impression cylinder shafts, means for individually adjusting the plate cylinder shafts about eccentric axes toward and from the impression cylinder shafts and securing them in their adjusted positions, and means for holding the impression cylinder shafts in a definite fixed position, whereby the impression cylinder shafts of the several printing units can be lined up and the plate cylinders can be adjusted independently thereafter.

2. In a printing press, the combination with an impression cylinder shaft having means at the end for connecting it end to end with the main shaft of another unit of the printing machine, a frame on which said shaft is mounted, and means for clamping said shaft against the frame in stationary position, of a plate cylinder shaft located adjacent thereto and mounted to swing on a longitudinal axis below it toward and from the impression cylinder, and means for adjusting the plate cylinder shaft about its pivot laterally and fixing it in adjusted position to secure the desired pressure between the two cylinders after the two units are coupled together.

3. In a printing machine, the combination of a plurality of complete printing presses each constituting a printing unit, and a folding unit, with means for connecting a shaft in each of said units together end to end in alignment, means for running the several units from these shafts, said shafts in the printing unit being the impression cylinder shafts, each of said impression cylinder shafts being mounted to swing on a pivot below it, a pair of plate cylinder shafts beyond the two impression cylinder shafts, means for individually adjusting the plate cylinder shafts about eccentric axes toward and from the impression cylinder shafts and securing them in their adjusted positions, and means for holding the impression cylinder shafts in a definite fixed position, whereby the impression cylinder shafts of the several printing units can be lined up with the folding

unit and the plate cylinders can be adjusted independently thereafter.

4. In a printing press, the combination of a plurality of units of the press, each having a main shaft coupled to the main shaft of the next unit end to end, one of said units being a printing unit and its main shaft constituting the shaft of one of the impression cylinders, said shaft being mounted on pivots below it and being movable laterally on the pivots, means for fixing the bearings of said shaft in stationary position against a side wall of the frame of the machine to hold it rigidly in position, a plate cylinder shaft located parallel thereto and mounted to swing on pivots below it, means for adjusting the bearings of the plate cylinder shaft about said pivots to secure the desired contact with the impression cylinder and for fixing it in adjusted position, inking mechanism, and means for driving the inking mechanism from the plate cylinder shaft.

5. In a printing machine, the combination with two printing press units, each having a separate frame for supporting the elements of that unit, of an element between them for connecting them together, the adjacent portions of the connecting element and the printing press frames provided with depressions filled with soft metal forming uniting seats for said adjacent portions and a perfect fit at each point and also providing a noiseless connection.

6. In a printing machine, the combination with a plurality of units, comprising printing press units and a folding unit having frames, with elements connecting the frames of said units and secured thereto by relatively soft metal cast seats between the adjacent portions of the frame and elements, thus avoiding machine finishing at these points, and providing a perfect fit at each point and also a noiseless connection.

7. In a printing machine, the combination with a printing unit comprising a frame and printing elements thereon, of a folding unit comprising a frame and folding elements thereon, elements between the two frames of a length less than the distance between the two frames or connecting them, said connecting elements and the printing unit frame and folding frame all having cast surfaces of soft metal, and seats cast into the spaces left between the said frames and elements in each instance for completing the connection and securely fastening the two frames together.

8. In a printing machine, the combination with printing units and a folding unit, of a base for each unit, means comprising portions of soft metal for uniting said bases to provide a noiseless perfect fitting connection, and similar means for mounting the main parts of the frames of the several units on their respective bases.

9. In a printing press, the combination of a

base and a frame supported on the base, the top of the base and the bottom of the frame being provided with depressed surfaces filled with relatively soft metal seats to support the frame noiselessly and with absolute accuracy on the base.

10. A printing press, the combination of a base and a frame supported on the base, the top of the base and the bottom of the frame being provided with surfaces at a distance from each other in the assembled machine, filled with relatively soft metal seats to support the frame on the base, a frame having means for supporting a web roll, and means 15 for mounting the last-named frame on the base comprising soft metal seats introduced between said frame and the base to support the web roll in accurate position on said base.

11. In a printing machine frame, the combination with a base, a frame part supported thereon for carrying the inking device and printing couples, and a frame supported by the last-named frame for carrying means for conducting the web away from the printing 25 couple, soft metal seats cast between the two frames and the base and printing couple frame for accurately supporting said frames one above the other and constituting the sole supports for each frame from the frame or 30 base below.

12. In a printing press, the combination with two printing couples, means for inking the plate cylinders thereof, and a web roll support having a flat surface for receiving the 35 studs of the web roll, and an open sided bearing at the end of said surface for receiving said studs, of a conical brake member keyed on one of the studs, a brake for engaging the conical brake member, means for adjusting the brake 40 longitudinally to bring it into proper relation to the brake member, and means for operating the brake laterally to force it towards the stud and apply the brake.

13. In a printing machine, the combination 45 with a plurality of printing units and means for delivering the webs therefrom, a printing couple for each unit, of means for slitting each web, turner bars for bringing the several pairs of slit webs all into a position one over the other, tension guide rolls, 50 one for each web, individual means for adjusting the guide rolls, a drag roll in position for receiving all of said webs one over the other on the surface thereof, a folding cylinder coupled directly to the shaft of the printing couple which drives the slitting means, and means on the folding cylinder shaft for positively driving the drag roll.

14. In a printing machine, the combination 60 with a plurality of printing units and means for delivering the webs therefrom, a printing couple for each unit, each unit having a driving shaft on which the impression cylinder is located, of means on each printing unit for 65 slitting each web, turner bars for bringing

the several pairs of slit webs all into a position one over the other, a drag roll in position for receiving said webs on the surface thereof; a folding cylinder coupled directly to the impression cylinder shaft of one of the printing couples which drives the slitting means, and means on the folding cylinder shaft for driving the drag roll.

15. A printing press, the combination with a printing couple, of a slitter roll, means for 70 rotating the slitter roll direct from one of the printing couple shafts, a shaft parallel with the slitter roll having arms fixed thereon, a lever pivoted to said arms, a slitter at the end of said lever, an adjustable spring 75 pin connected with the other end of the lever for adjusting the slitter in proper relation to the slitter roll, and means for swinging the shaft, taking the slitter with it out of or into contact with the slitter roll.

16. A printing press, the combination with a slitter roll, a shaft parallel with the slitter roll having arms fixed thereon, a lever pivoted to said arms, a slitter at the end of said lever, an adjustable spring pin connected with the 80 lever for adjusting the slitter in proper relation to the slitter roll, a handle on said shaft, a latch pivoted on the handle and having a bolt guided by the handle, and a lug in fixed 85 position having notches for receiving the bolt in its two extreme positions.

In testimony whereof I have hereunto affixed my signature.

HENRY A. WISE WOOD.
